UNITED STATES PATENT OFFICE.

RUDOLPH H. BECK, OF PHILADELPHIA, PENNSYLVANIA, ASSIGNOR TO THE GIRARD BUTTON MANUFACTURING COMPANY, LIMITED, OF SAME PLACE.

BUTTON-MAKING MACHINERY.

SPECIFICATION forming part of Letters Patent No. 630,645, dated August 8, 1899.

Application filed March 13, 1899. Serial No. 708,826. (No model.)

To all whom it may concern:

Be it known that I, RUDOLPH H. BECK, a citizen of the United States, residing at the city of Philadelphia, in the county of Philadelphia and State of Pennsylvania, have invented certain new and useful Improvements 5 in Button-Making Machinery, of which the following is a specification.

My invention has relation to a button-making machine, and in such connection it relates more particularly to the construction and arrangement of the countersinking or turning tool and the drills, together with the mechanism for operating said tool and drills.

15 In a companion application filed the 10th day of March, A. D. 1899, under the Serial No. 708,507, the arrangement and construction of a preferred form of chucks for the machine, the table carrying said chucks, and the 20 mechanism for operating the chucks and table have been illustrated, described, and claimed. The present application is designed to cover the preferred forms of drilling and turning tools, which, although generally adapted 25 for use with any type of chuck, are especially adapted for use with the chucks described in said companion application.

The principal objects of my invention are, first, to provide a turning or countersinking 30 tool of peculiar construction and arrangement, together with mechanism for properly centering or adjusting the tool with respect to the blank to be turned and mechanism for lowering the tool into operative position and 35 elevating it therefrom at the proper intervals of time, and, second, to provide two sets of drills, each drill being of peculiar construction and arrangement, together with mechanism for adjusting and properly centering 40 each set of drills and mechanism for elevating and lowering the sets of drills at the proper intervals of time.

To this end my invention consists, first, in providing in a button-making machine a countersinking or turning tool and its holder, said 45 tool being adapted to be quickly and easily inserted, withdrawn, and adjusted in its holder and said holder being adapted to be quickly and easily adjusted in vertical and horizontal 50 planes to properly center the tool with regard

to the blank to be turned; second, in providing in a button-making machine, in connection with a countersinking or turning tool holder and the drill-holders, mechanism for elevating and depressing the tool and drill 55 holders at stated intervals of time and means for adjusting said mechanism, whereby the movement of the tool and drills downward may be quickly and easily increased or decreased; third, in providing in a button-making machine drills having the spindles arranged in sets of two in a drill-holder, said drill-spindles being adapted to be quickly and easily inserted, withdrawn, and adjusted in the holder and said holder being adapted to 60 be quickly and easily adjusted in vertical and horizontal planes to properly center the drills with regard to the blank to be drilled, and, fourth, in providing in a button-making machine a drilling-tool comprising a hollow stem 65 or spindle arranged obliquely in a holder and having a removable lower portion of conical shape and adapted to receive the drill-point and means for adjusting and clamping said drill-point in said conical end portion of the 70 spindle.

The nature and scope of my invention will be more fully understood from the following description, taken in connection with the accompanying drawings, forming part thereof, 80 in which—

Figure 1 is a side elevational view of a button-making machine embodying main features of my present invention. Fig. 2 is a top or plan view thereof. Fig. 3 is a side elevational view, enlarged, of the countersinking or turning tool and its holder detached from the machine. Fig. 4 is a similar view of the reverse side of said tool and its holder, illustrating the mechanism for elevating and lowering the holder and the means for adjusting said mechanism. Fig. 5 is a top or plan view of Fig. 4, partly sectioned, to more fully illustrate the construction and arrangement of certain of the parts. Fig. 6 is a front elevational view, still further enlarged, of the lower end of the tool and holder and illustrating in section a chuck and blank beneath the tool. Fig. 7 is a view at right angles to Fig. 6, a portion of the tool-holder being sectioned to 95 100

illustrate the manner in which the tool is inserted therein. Fig. 8 is an underneath plan view of Fig. 7. Fig. 9 is a front elevational view, enlarged, of one set of the drills and illustrating in vertical section the drill-holder and a chuck and blank below the drill-points. Fig. 10 is a view, partly sectioned, taken at right angles to Fig. 9. Fig. 11 is a side elevational view of one set of drills and their holder detached from the machine. Fig. 12 is a rear-elevational view of the holder illustrated in Fig. 11. Fig. 13 is a front elevational view, enlarged, of the lower end of one of the drill-spindles. Fig. 14 is a vertical sectional view taken at right angles to Fig. 13. Figs. 15 and 16 are cross-sectional views taken, respectively, on the lines 15 15 and 16 16 of Fig. 14; and Fig. 17 is a perspective view, enlarged, of the block clamping the drill-point in the end of the spindle.

Referring to the drawings, and particularly to Figs. 1 and 2 thereof, a represents the bed-plate of the machine, upon which are properly supported the necessary standards and the framework of the machine. In an end standard a' is supported the main power-shaft a^2 , which by preference is arranged vertically and carries at or near its upper end the two pulleys a^3 and a^4 , adapted, respectively, through suitable belting, to rotate the countersinking or turning tool and the two sets of drills. The shaft a^2 also serves to operate the table a^5 with an intermittent or step-by-step movement, so that the same may present the chucks a^6 , arranged in series on said table, successively to the turning-tool and to each set of drills.

The construction and arrangement of the table a^5 and of its chucks a^6 , as well as the means for operating the same, form no part of the present invention, but form the subject-matter of a companion application filed on the 10th day of March, A. D. 1899, under the Serial No. 708,507. For the proper understanding of the present invention a detailed description of the table and chucks is not deemed necessary. It is sufficient to state that each chuck a^6 has two jaws a^7 sliding beneath a plate a^8 , which is perforated to admit the blank A, and that these jaws a^7 close down upon the periphery of the blank and clamp it in the chuck during the turning or countersinking of the blank and during the two successive drilling operations, which will be hereinafter described.

The pulley a^3 operates, through the belt a^9 , a pulley a^{10} , keyed or otherwise secured to a vertically-arranged shaft b , which rotates in a suitable bearing b' , from which extends a bracket b^2 , having a slotted end b^3 , secured to an upright or standard of the machine. The bracket b^2 serves as a brace for the shaft b , and its slotted connection with a stationary part of the machine permits of an adjustment of the bearing b' to compensate for the adjustment of the other bearing for the shaft b , which, as hereinafter explained, also consti-

tutes the adjustable support for different members of the holder for the countersinking-tool.

Referring now to Figs. 3 to 7, inclusive, the shaft b carries at its lower end a block d , which rotates with the shaft and has on its under face a depending gage-plate d' , which, by means of the bolt d^2 , working in the slot d^3 of the plate d' , may be adjustably secured to the block d , so that it may be shifted toward or away from the center of the shaft b (which forms the axis of rotation of the block d) and locked in the required position. The lower edge d^4 of this plate d' forms an abutment for the cutting edge of the countersinking-tool e . The tool e , as illustrated in Figs. 7 and 8, is adapted to be slipped into an obliquely-arranged slot e' in a holding-block e^2 and to be pressed upward against the upper face of said slot by a flat spring e^3 . The spring e^3 thus insures the proper guiding of the tool e in the holding-block e^2 , and the plate d' serves as a guide or stop to indicate that the tool e projects from the slot the required distance. The holding-block e^2 is supported by the block d at an angle of approximately forty-five degrees to the axis of rotation of said block, and it is adjustable in the plane of its support by means of a dovetailed extension e^4 , sliding in a corresponding slot in the block d . The holding-block e^2 when shifted to its required position on the block d is maintained in that position by the set-screws d^5 . The tool e when properly guided in the slot e' is held therein by means of set-screws e^6 or equivalent fastening means. The tool e is thus centered with respect to the blank by the plate d' and by the shifting of its holder e^2 upon the block d . The shaft b and the block d may also be centered with respect to the chuck by the following preferred means: The shaft b passes through two eyes f , projecting from a bracket f' , which is adapted to slide on a longitudinally-arranged dovetail projection f^2 of a block f^4 , which block f^4 is provided with a dovetail projection f^5 , adapted to slide in a horizontally-arranged complementary groove f^6 of a slide f^7 . The arrangement is such that the shaft b is shifted by the movement of the bracket f' longitudinally on the block f^4 in a direction toward or away from the slide f^7 , and the shaft b and bracket f' together are shifted on the slide f^7 horizontally and in a direction parallel to the face of said slide. The shaft b may thus be shifted at any angle in planes parallel to its axis of rotation, the movement of the shaft being compensated for by moving the upper bearing b' and the bracket b^2 , which braces said bearing b' by connecting it by a slotted connection b^3 with an immovable portion of the framework.

Returning now to the block d , which rotates with the shaft b and carries the tool-holder e^2 , it will be observed that the holding-block e^2 is carried at one side of said block d , and hence if the block d were not properly bal-

anced with respect to the shaft b there would be a tendency of the block d to rock during its rotation with the shaft b . To overcome this objection, a counterweight d^5 is secured 5 to the block d at a point diametrically opposite to the point at which the tool-holding block e^2 is carried. This counterweight d^5 is preferably adjustable on the block d , and hence is secured thereto by means of a bolt d^6 , passing through a slotted ear d^7 of the counterweight, as clearly illustrated in Fig. 4.

Referring to Fig. 5, when the shaft b is shifted by the bracket f' away from the block f^4 it is preferable that the connection between 15 the bracket f' and block f^4 be strengthened, since the rotation of the shaft b will exert a torsional strain upon said bracket f' . To strengthen or brace the connection of the bracket f' with the block f^4 , a projection f^8 20 is formed on the ears f of said bracket f' , and this projection f^8 is locked to a corresponding projection f^9 on the block f^4 by an adjustable screw-bolt f^{10} . It will be understood that the bracket f' when properly shifted in the block f^4 25 is locked to said block by means of set-screws f^{11} or similar means passing through the bracket f' and impinging upon the dovetail portion of the block f^4 , and in the same manner the block f^4 is locked to required position on the slide f^7 by means of the set-screws f^{12} .

In the operation of the machine it is necessary at stated intervals of time to lower the tool e into operative position with regard to the blank A and after the tool has performed 35 its function to elevate said tool into inoperative position with respect to the blank. The shaft b and the tool e having been properly centered, as hereinbefore described, the raising and lowering of said tool are accomplished 40 by the following preferred mechanism.

Referring to Figs. 1 to 5, inclusive, the slide f^7 is provided with a rack g , properly secured by screws or otherwise to the rear face of said slide, and in said rack g a pinion g' is adapted to mesh. This pinion g' is loosely supported upon a stud or pin g^2 on one of the standards of the machine. Upon this stud g^2 one end of a rock-arm g^3 is also loosely supported. A bolt g^4 adjustably secures the rock-arm g^3 to the pinion g' in a manner and for a purpose hereinafter described. The free end of the rock-arm g^3 is provided with a roller g^5 , which by preference is adjustable 55 in a slot of said rock-arm, and this roller g^5 bears upon the periphery of a cam g^6 , the rock-arm g^3 being normally depressed by the spring g^7 for this purpose. The cam g^6 is carried by a shaft g^8 , to which motion is conveyed from the power-shaft a^2 in any suitable manner. As the cam g^6 rotates it will alternately raise and lower the rock-arm g^3 , which oscillates upon the stud g^2 and through its connection with the pinion g' serves to oscillate said pinion. The oscillation of the pinion g' raises and lowers the rack g and causes the slide f^7 to move up or down upon

a stationary portion of the machine. The slide f^7 carries with it the bracket f' , which through its ears f bears upward upon a collar b^4 on the shaft b and downward upon the block d . The movement of the slide f^7 will therefore, through the bracket f' , serve to elevate or depress the shaft b , and its block d , which carries the tool e , will be lifted or depressed. 75

In the turning or countersinking of blanks of different thicknesses it is necessary to adjust the downward movement of the tool. To accomplish this, the connection of the rock-arm g^3 with the pinion g' is made adjustable 80 in the following manner: The bolt g^4 passes through a curved slot g^9 in the rock-arm g^3 , and the position it occupies with relation to the respective ends of the slot is regulated by means of the adjusting-screws g^{10} . 85

Referring now to Fig. 4, if it is found desirable to depress the shaft b and its tool e a greater distance than is normal the upper screw of the set-screws g^{10} is loosened, and the pinion g' is turned upon its stud g^2 from left to right, thus depressing the rack g and slide f^7 below its normal position, and hence lowering the shaft b and countersinking-tool toward the table and chucks. The rock-arm g^3 upon being locked to the bolt g^4 by advancing the lower screw of the set-screws g^{10} will now throw the pinion as heretofore; but of course the movement of the rack g and tool e will range between points lower than is normally the case, and the tool will be caused to enter the blank A more deeply. The rack g and slide f^7 may be elevated to prevent the tool e from entering the blank A too far by a similar adjustment of the pinion g' on its stud g^2 , but of course in an opposite direction. 95 The blank A after being turned or counter-sunk is then presented to the mechanism for drilling the holes or eyes. Usually each blank is provided with four eyes or holes, and hence in the drawings there is illustrated mechanism for drilling the four eyes, although it is to be understood that if required but two eyes may be drilled in each blank by the same machine by simply removing the drill-points from two of the drill-spindles. 105 110 115

In the present machine the drills are arranged in two sets, each set comprising two drills, and both sets are adapted to be brought into and out of operative position with respect to the blank. Inasmuch as the arrangement 120 and operation of both sets of drills are the same, description of but one set is all that will be required.

Referring to Figs. 9 to 17, inclusive, each drill proper consists of a spindle m , having 125 at its upper end a pulley m^1 and at its lower end a removable conical portion m^2 , in which the drill-points m^3 are adapted to be securely clamped. The spindle m and its conical end portion m^2 are both hollow, the spindle m 130 preferably for only a portion of its length, to receive the upper portion of the drill-points m^3 . The conical portion m^2 is provided with a vertically-arranged slot m^4 , the lower end

of which is curved, as at m^5 , and this slot extends from the face to the interior opening in the conical end m^2 . In this slot m^4 is adapted to be slid a bar m^6 , having one face 5 grooved, as at m^7 , to fit closely down upon the drill-point m^3 . This bar m^6 is clamped down upon the drill-point m^3 by means of a set-screw m^8 or similar device, as illustrated in Figs. 14 and 16. The curved lower end 10 m^5 of the slot m^4 permits one end of the bar m^6 to be lifted outward to release the drill-point when the set-screw m^8 is released. In drills of this character it is essential in drilling two or more holes in very small blanks 15 that the drill-points be brought very closely together. This is accomplished in the following manner: Each spindle m of a set is guided obliquely in a holder n in such a manner that the drill-spindles converge until they 20 almost meet at the points where their conical ends m^2 are screwed into the spindle proper. (See Fig. 9.) The ends m^2 being conical, the drill-points m^3 are prevented from crossing, but are guided into substantially 25 parallel relationship, while closely approaching each other. The conical ends m^2 being readily removable from the spindles m , any accident to a drill-point m^3 can be remedied by unscrewing the conical end and re- 30 moving both end and drill-point and replacing the same with a new end and a new drill-point without disturbing the spindles proper. The holder n for each set of spindles is adjustable much in the same manner as is the 35 bracket f' , which guides the shaft b of the countersinking or turning tool e —that is to say, the holder n slides on a block n' toward or away from the slide n^2 , and the block n' is movable on the slide n^2 in a direction parallel 40 with said slide n^2 and at right angles to the movement of the holder on the block n' . As illustrated in Figs. 1 and 2, the slide n^2 is common to both sets of drills and is elevated and depressed in the same manner as is the 45 slide f' of the tool e —that is to say, a pinion n^3 operates a rack n^4 , secured to the slide, and this pinion n^3 is operated by a rock-arm n^5 by means of a cam n^6 on the shaft g^8 in the same manner as the heretofore-described 50 movement of the rock-arm g^3 , cam g^6 , and shaft g^8 . The cams g^6 and n^6 and the rock-arms g^3 and n^5 are arranged so that the sets of drills and the tool e are simultaneously elevated and depressed. The throw of the 55 rock-arm n^5 is adjusted in the same manner as is the throw of the rock-arm g^3 , but independently thereof. Where the blank is to be drilled by two sets of drills, as illustrated in Fig. 2, it sometimes happens that the drill- 60 points of one set will not be adjusted properly, so as to drill holes in the blank at right angles to the holes drilled by the points of the other set. This adjustment of the angular position of the drill-points without separating or spreading the drills, however, may 65 be obtained, as illustrated in Fig. 9, by swiveling the holder n in the bracket n' and using

a set-screw n^7 to fix the holder in the bracket after the holder and drills have been turned to required position. 70

Having thus described the nature and objects of my present invention, what I claim as new, and desire to secure by Letters Patent, is—

1. In a machine of the character described, 75 a countersinking or turning tool and a drilling-tool, means for independently centering each tool, and means for simultaneously elevating and depressing both tools, substantially as and for the purposes described. 80

2. In a machine of the character described, a turning-tool and a drilling-tool, means for independently centering each tool, mechanism for simultaneously elevating and depressing both tools, and means for adjusting said 85 mechanism independently for each tool, substantially as and for the purposes described.

3. In a machine of the character described, a turning-tool, a holder for said tool, means for centering said holder, a drilling-tool and 90 its holder, means for centering the holder for said drilling-tool, a slide adapted to elevate and depress the turning-tool and its holder, a slide adapted to elevate and depress the drilling-tool and its holder, and mechanism 95 adapted to operate both slides simultaneously, substantially as and for the purposes described.

4. In a machine of the character described, a turning-tool and its holder, means for centering said holder, a drilling-tool and its holder, means for centering said drilling-tool holder, a slide adapted to elevate and depress the turning-tool and its holder, a slide adapted to elevate and depress the drilling-tool and 105 its holder, mechanism for operating both slides simultaneously, and means for adjusting said mechanism independently for each tool, substantially as and for the purposes described. 110

5. In a machine of the character described, a tool-holder, a slide carrying said tool-holder, a rack secured to said slide, a pinion meshing with said rack, a rock-arm adapted to oscillate said pinion, mechanism for operating said 115 rock-arm, and means for adjusting said rock-arm with relation to the pinion, whereby the movement of said pinion may be varied, substantially as and for the purposes described.

6. In a machine of the character described, 120 a rotatable shaft, a block rotating therewith, a tool-holding block supported by said block at an angle to the axis of rotation of said block and shaft, said tool-holding block being adjustable in the plane of its support and slot- 125 tened in a plane at an angle to the axis of rotation of the shaft, and a tool adjustably secured in the slot of said tool-holding block, substantially as and for the purposes described. 130

7. In a machine of the character described, a rotatable shaft, a block carried at one end of said shaft, a counterweight secured to said block on one side of the shaft, a tool-holder se-

cured to said block diametrically opposite to the counterweight, and a countersinking or turning tool secured in said holder at an angle to the axis of rotation of the shaft, substantially as and for the purposes described.

8. In a machine of the character described, a rotatable shaft, a block carried by said shaft, a counterweight secured to said block on one side of the shaft, means for adjusting said counterweight, a tool-holder secured to said block diametrically opposite to the counterweight, and a countersinking or turning tool secured in said holder at an angle to the axis of rotation of said shaft, substantially as and for the purposes described.

9. In a machine of the character described, a block, a rotatable shaft carrying said block, a gage-plate depending from said block, a tool-holder carried by said block and slotted at an angle to the axis of rotation of the shaft, and a tool adapted to be inserted in the slotted holder and having its cutting end abutting against said gage-plate, substantially as and for the purposes described.

10. In a machine of the character described, a block, a rotatable shaft carrying said block, a gage-plate depending from said block, means for adjusting said gage-plate, a tool-holder carried by said block and slotted at an angle to the axis of rotation of the shaft, and a tool adapted to be inserted in the slotted holder and having its cutting end abutting against the gage-plate, substantially as and for the purposes described.

11. In a machine of the character described, a tool-holder having a slot arranged at an angle to the axis of rotation of the tool-holder, means for rotating said tool-holder, a tool adapted to be inserted in the slot of the holder, a spring adapted to press the tool against the base of said slot, and means for clamping the tool to the tool-holder, substantially as and for the purposes described.

12. In a machine of the character described, a hollow spindle, a hollow conical end removably secured to said spindle and vertically slotted, a drill-point adapted to be inserted in said conical end, a grooved bar adapted to be inserted in the slot of said end, and means adapted to clamp the grooved face of said bar down upon the drill-point, substantially as and for the purposes described.

13. In a machine of the character described, a holder, a bracket traversed by and to which said holder is swiveled, two drilling-tools adapted to rotate in said holder, and means for adjusting the holder in the bracket, whereby the angular position of the drill-points of the drilling-tools may be varied without spreading or separating said tools, substantially as and for the purposes described.

In testimony whereof I have hereunto set my signature in the presence of two subscribing witnesses.
